UNITED STATES PATENT OFFICE.

HENRY F. GAUSS, OF MOSCOW, IDAHO, ASSIGNOR TO HEINE BOILER COMPANY, OF ST. LOUIS, MISSOURI, A CORPORATION OF MISSOURI.

AIR HEATER.

Application filed January 14, 1926. Serial No. 81,333.

This invention relates to heating devices of the kind that are used for causing one gaseous medium to be heated by another gaseous medium of a higher temperature, 5 and particularly air heaters of the recuperative type composed of a plurality of metal plates combined in such a manner as to form air passageways and gas passageways arranged in alternate relation and disposed so 10 as to cause the gases which escape from a boiler to flow through said gas passageways, and thus heat air which is being drawn or forced through said air passageways to the furnace of the boiler.

15 The main object of my invention is to provide a recuperative air heater of the plate type, that is efficient, inexpensive to manufacture and of such construction that air cannot leak into the gas passageways, and 20 thus reduce the temperature of the gases flowing through said passageways.

Figure 1 of the drawings is a side elevational view of an air heater constructed in accordance with my invention, combined 25 with a water tube boiler.

Figure 2 is a front elevational view of said heater.

Figure 3 is a vertical longitudinal sectional view of said heater, taken through one 30 of the air passageways.

Figure 4 is a horizontal transverse sectional view through a portion of the heater, illustrating the devices that are used at the intake ends and discharge ends of the air 35 passageways to hold the plates spaced apart, said view being taken on the line 4-4 of Figure 3.

Figure 5 is a horizontal transverse sectional view, taken through the intermediate 40 portion of the heater, as, for example, on the line 5-5 of Figure 3.

Figure 6 is a horizontal transverse sectional view similar to Figure 5, illustrating a slight modification of my invention.

45 Figure 7 is a horizontal transverse sectional view similar to Figure 4, illustrating still another form of my invention; and

Figure 8 is a horizontal transverse sectional view, similar to Figure 5 of an air heater of the kind shown in Figure 7.

In the drawings A designates a boiler of any preferred type herein illustrated as a water tube boiler and B designates an air

heater arranged in such a manner that the gases which escape from said boiler will flow 55 through said air heater and thus heat air which is being supplied to the furnace of the boiler to support combustion. As shown in Figure 1 the air heater B is arranged at the upper end of the boiler in the path of the escaping gases indicated by the arrows x a fan or other suitable suction device C being used to cause the gases to flow through the air heater and a blower or other suitable device D being used to cause air to flow 60 through the heater B and then pass to the grate or to the combustion chamber of the boiler as indicated by the arrows y.

The air heater B is made up of a plurality of thin flat metal plates 1 of substantially 70 oblong shape in outline, arranged vertically in parallel relation, and flat metal bars and spacing devices combined with said plates in such a way as to form a plurality of open-ended gas passageways x' through which 75 the gases flow longitudinally of the heater, and a plurality of air passageways y' between said gas passageways, each of said air passageways being provided at one end with an inlet opening located in one side of the 80 heater and provided at its opposite end with a discharge opening located in the opposite side of the heater. In the form of my invention herein illustrated the heater B is provided at its upper end with a tubular intake 85 2 common to all of the air passageways y' that projects laterally from the rear side of the heater, and said heater is provided at its lower end with a tubular discharge 3 common to all of the air passageways that 90 projects forwardly from the front side of the heater, as shown in Figures 1 and 3.

The gas passageways x' are formed by the plates 1 and flat metal bars 4 arranged between pairs of said plates at the longitudinal 95 side edges of same and extending the entire length of the heater, thus forming vertically-disposed gas passageways that have intake openings located in the bottom of the heater and discharge openings located in the 100 top of the heater. The air passageways y' are also formed by the plates 1 and by flat metal bars that are combined with said plates in such a way as to form air passageways between the gas passageways that have 105 lateral intake openings in the rear side of the

heater and lateral discharge openings in the front side of the heater. As shown in the drawings, the upper and lower ends of the air passageways y' are closed by horizontal-
5 ly-disposed bars 5 that are arranged between the respective pairs of plates 1, and the side edges of said air passageways are formed by short metal bars 4^a of less length than the bars 4, arranged between the respective pairs
10 of plates 1 parallel to the bars 4 and extending from the ends of the heater to the points where the intake and discharge openings of the air passageways are located. In order to hold the plates 1 spaced apart at the points
15 where the intake and discharge openings of the air passageways y' are located, spacing devices 6 are arranged between the plates 1 in the inlet and discharge openings of the air passageways, as shown in Figure 4.
20 Any suitable means can be used for combining the plates 1 with the bars and spacing devices above referred to, but I prefer to clamp said parts securely together by long bolts 7 that extend transversely of the
25 heater and which pass through the plates 1, bars 4 and 4^a and spacing devices 6, as shown in Figures 4 and 5, the spacing devices 6 being of tubular form. An air heater of the construction above described
30 is strong and rigid and it is inexpensive to manufacture, as it is built up principally of flat metal plates and flat metal bars that are clamped together by transversely-disposed bolts which pass through aligned openings
35 in said plates and bars. Moreover, such a heater is exceptionally efficient, as the air flows through the heater in a direction opposite to the flow of the gases, and the members that divide the air passageways from
40 the gas passageways consist of relatively thin metal plates that absorb heat rapidly from escaping gases and transmit said heat to the inflowing air. The air passageways y' are preferably provided with hori-
45 zontally-disposed baffles 8 arranged in staggered relation, as indicated in Figure 3, so as to cause the air to make a plurality of passes and flow in a zig-zag path through the air passageways of the heater. After
50 the plates 1, bars 4 and 4^a and spacing devices 6 have been assembled and clamped together the joints in the front and rear sides of the heater formed by the longitudinal side edges of the plates 1 and the bars 4 and
55 4^a interposed between the same are sealed, preferably by welding, as indicated by the reference character 9 in Figure 5, so as to eliminate the possibility of air entering the gas passageways x' , and thus reducing the
60 temperature of the gases passing through the heater.

In Figure 6 I have illustrated an air heater that embodies all of the desirable features and characteristics of the air heater
65 shown in Figures 4 and 5 and which has the

added advantage of requiring only one-half the number of welded joints to produce gas passageways whose longitudinal side edges are air-tight. In said heater every alternate plate 1^a is provided at one of its longitudinal edges with an integral, laterally-projecting flange 10 that is connected by a welded joint 9^a to the adjacent longitudinal side edge of the plate 1^a with which it co-
70 operates to form a gas passageway, the flanges 10 being arranged on the outsides of the long bars 4 that form the longitudinal side edges of the gas passageways.
75

In instances where it is desired to entirely eliminate welded joints at the longitudinal side edges of the plates which separate the air passageways from the gas passageways, without however, impairing the efficiency of the heater, the heater can be built up of flat, oblong-shaped plates 1, as shown in Figures 80 7 and 8, with pairs of long and short spacing bars and asbestos packing material arranged between the longitudinal side edges of said plates at the front and rear sides of the heater. Thus, as shown in Figure 8, 85 pairs of long bars 40 can be arranged between the plates 1 at the front and rear sides of the heater, and the space between said bars can be filled with asbestos or other packing material 41. Similar pairs of short 90 bars 40^a are arranged between the plates 1 to form the edge walls of the air passageways y' , the spaces between said bars 40^a also being filled with asbestos. At the points where the inlet and discharge openings of the air passageways are located tubular spacing devices 6^a are arranged between the pairs of plates 1 that constitute the air passageways, as shown in Figure 7.
95

It will, of course, be understood that it 100 is immaterial, so far as my invention is concerned, whether the air heater B is arranged in a vertical position or in a horizontal position, and it is also immaterial which particular group of passageways in said heater 105 is used for the escaping gases and which group of passageways is used for the inflowing air. Likewise, it is immaterial what means is used to produce tight joints at the longitudinal side edges of the gas passageways, so long as the side edges or longitudinal edges of the two groups of passageways of the heater are formed by flat metal bars 110 that are arranged between the plates that separate the inflowing air from the escaping 115 gases.
120

Having thus described my invention, what I claim as new and desire to secure by Letters Patent is:

An air heater composed of a plurality of 125 flat metal plates of the same size arranged in parallel relation, flat metal bars of substantially the same length as said plates arranged between the longitudinal edge portions of pairs of said plates so as to form 130

passageways having inlet and discharge openings located at the ends of the heater, flat metal bars of less length than the plates arranged between the respective pairs of plates so as to form passageways having lateral inlet and discharge openings located at the front and rear sides of the heater, spacing devices arranged between the respective pairs of plates in said lateral inlet and discharge openings, and bolts that pass ¹⁰ transversely through said plates, bars and spacing devices so as to clamp them tightly together.

HENRY F. GAUSS.
